UNITED STATES PATENT OFFICE.

SARA KINSCELLA, OF BRIDGEPORT, CONNECTICUT.

STRAIGHT-BACK CORSET.

1,216,326.

Specification of Letters Patent. Patented Feb. 20, 1917.

Application filed September 14, 1916. Serial No. 120,121.

To all whom it may concern:

Be it known that I, SARA KINSCELLA, a citizen of the United States, and resident of Bridgeport, in the county of Fairfield and 5 State of Connecticut, have invented certain new and useful Improvements in Straight-Back Corsets, of which the following is a specification.

This invention relates to improvements in 10 corsets for women and is particularly designed for stout women.

The purpose of the invention is to design 15 and construct a corset which will better accommodate the surplus flesh of stout women and especially to prevent the flesh from overhanging the top edge of the back of the corset when in position upon the wearer, and yet present a smooth, uniform and neat appearance upon the outside; further to provide 20 a corset for the purposes designated which will be cooler and more comfortable to wear, allowing more freedom of motion and expansion of the breast, shoulders and shoulder blades and further to provide a feature 25 which may be easily incorporated in the commercial types of straight back corsets; and finally to provide a simple and improved form of construction whereby a corset is produced having the desired lines for a straight 30 back corset and one which will not push up as common with ordinary corsets.

With these and other objects in view the invention resides and consists in the construction and novel combination and arrangement 35 of parts hereinafter more fully described, illustrated in the accompanying drawings, and pointed out in the claims hereto appended, it being understood that various changes in the form, proportion, 40 size and minor details of construction within the scope of the claims may be resorted to without departure from the spirit or sacrificing any of the advantages of the invention.

Similar characters of reference denote like 45 or corresponding parts throughout the several figures of the accompanying drawings forming a part of this specification, and upon which,

Figure 1 shows an inside front view of my 50 improved corset, laid open flat and full width.

Fig. 2 shows a central vertical sectional

view of the same corset as it would appear when positioned upon a figure, and 55

Fig. 3 shows a horizontal section looking down and taken through the belt line of Fig. 2.

Referring in detail to the characters of reference marked upon the drawings A represents the corset as a whole, B a front steel carrying the loops forming a part of the clasp and C a co-acting front steel carrying the studs of the clasp. D is a lacing which is threaded through eyes G of the stick L 60 and through similar eyes E in the vertical edge portion F of the front of the body of the corset.

H represents the fabric sections of the 70 body of the corset which may be shaped or patterned in the usual or any preferred manner and vertically stitched together. I represents the stays of which there may be any desired number and arranged according to 75 the cut and pattern of the corset desired.

As shown these stays for the most part as will be noted in this particular design of corset do not run to the bottom edge leaving that more flexible as is the custom with the 80 numerous styles of low cut corsets.

The feature of the invention is clearly shown in the three figures and as will be noted includes the employment of a strap J that is attached to the inside of the back of 85 the corset in line with the waist line, said strap being only secured at its end portions K—K and there stitched into a vertical seam adjacent to the stays I. The length of the strap employed is slightly less than the 90 width of that part of the corset lying directly back of it and between the two attached ends of the strap so as to insure a fullness of the corset back of the strap thereby producing a comparatively straight 95 back corset the strap of which closely fits the figure at the waist line and below.

Additional waist bands M and N are employed and extend from the attached ends of the strap across and downward through 100 the front of the corset, being stitched thereto and made an integral part of the body of the corset so as to lend additional strength and endurance to the corset around the waist and to furnish better support to the abdomen from the back. 105

- When applied as shown in Figs. 2 and 3 the strap in the back naturally hugs and tightens against the waist of the wearer, leaving the body of the corset at this point free and comparatively straight and thus forming additional room to accommodate the flesh of the shoulder, and yet to form a waist line that is snug and comfortable and a corset back that is as straight as desired.
- 10 A corset of this kind may be fastened either in the front or on the side, as may be preferred and as before stated, the feature of the invention is applicable to various designs.
- 15 Having thus described my invention what I claim and desire to secure by Letters Patent is:
1. In a corset of the class described, the combination with a body portion, of a strap arranged upon the inside of the back at the

waist line and having its two ends secured to the inside walls of the corset at distant points and its intermediate portion free.

2. In a corset of the class described, the combination with a body portion, of a strap 25 arranged upon the inside and on the waist line having its two ends secured to the inside walls of the corset and its intermediate portion free, said strap being of a shorter length than the portion of the corset lying in its 30 rear and between the points of attachment of the strap.

Signed at Bridgeport, in the county of Fairfield and State of Connecticut, this 8th day of September, A. D. 1916.

SARA KINSCELLA.
